UNITED STATES PATENT OFFICE.

EDWARD J. TEKULVE, OF COVINGTON, KENTUCKY.

ATTACHMENT FOR BELLS.

1,369,496.

Specification of Letters Patent. Patented Feb. 22, 1921.

Application filed October 16, 1920. Serial No. 417,321.

To all whom it may concern:

Be it known that I, EDWARD J. TEKULVE, a citizen of the United States, residing at Covington, in the county of Kenton and State of Kentucky, have invented certain new and useful Improvements in Attachments for Bells, of which the following is a specification, reference being had to the accompanying drawings.

10 This invention relates to bells and particularly to an attachment for bells such as used by churches, schools, factories, etc.

An object of the invention is to provide an attachment for a conventional form of bell whereby the bell is rung during the interval of silence caused by the travel of the clapper of the bell from one side to the other or movement of the bell from one side to the other of the clapper.

20 Another object is to provide an attachment of this character including one or more auxiliary clappers disposed exteriorly of the bell and adapted to alternate with each other and the conventional form of clapper 25 of the bell, to ring the bell according to the direction in which the bell is moving and in this way produce only a slight interval between each stroke of the clappers so that the lost movement of the bell is utilized to 30 operate the auxiliary clappers.

A still further object of the invention is to provide an attachment of this character including a pair of auxiliary clappers disposed exteriorly of the bell, said clappers being normally held in spaced relation to the exterior surface of the bell so as to prevent interference with the vibration of the bell after the same is struck by the clapper.

35 A still further object of the invention is to provide a device of this character including a support carried by the bell and movable therewith, said support being provided with a plurality of movable clappers adapted to engage the bell when the bell is moved in the 40 direction of the clapper.

With the above and other objects in view, the invention consists in the improved construction and arrangement of parts to be hereinafter more particularly described, 50 fully claimed and illustrated in the accompanying drawings, in which:—

Figure 1 is a longitudinal sectional view of a bell showing the invention applied, and

Fig. 2 is a front elevation.

55 Referring to the drawings, 5 designates a conventional form of bell in the interior of

which a conventional form of clapper 6 is pivoted. This clapper is intended to be used in the well-known manner. The bell is provided with the usual yoke 7 including 60 the oscillating stub shafts 8 adapted to engage the bearings in the turret, not shown.

In order to sound the bell during intervals of sound caused by movement of the clapper 6 from one side to the other, I provide a 65 novel attachment comprising a support 9 which is secured to the top of the bell between the yoke and bell. The end portions 10 and 11 of the support 9 are extended downwardly and outwardly in spaced relation to the exterior surface of the bell and in diametrically spaced relation to each other. Each end portion is provided with a pair of arms 12 which project from the exterior surface of said end portions and are 70 75 adapted to receive one end of a clapper 13, the clapper being pivoted between the ears by means of a pintle 14. This clapper is intended to move freely between the ears through force of gravity. The shank 14 of 80 the clapper extends below the extremity of the end portion to which it is connected and is provided with a hammer head 15, said head being disposed adjacent the lower edge 85 of the bell.

To prevent the hammer head 15 from interfering with the vibration of the bell during the ringing of the same, and at the same time to permit the clapper to readily strike the bell, I provide a novel leaf spring 90 16, the end 18 being semi-circular in cross section. The end 17 and central portion of the spring is flat so as to permit the spring to be readily secured to the end portions of the support. One of these springs is secured 95 to the outer surface of the end portions 10 and 11, and extends downwardly between the shank 14 and the adjacent exterior surface of the bell. The end 18 of the spring is normally engaged with a portion of the 100 head 15 so as to hold said head in spaced relation to the bell. At the same time the weight of the clapper is such as to overcome the resistance of the spring upon movement of the bell in the direction of the clapper so 105 as to permit the head 15 to strike the bell.

In the operation of the device, the bell is operated in the usual manner to cause the clapper 6 to strike the interior surface of the bell and sound the same. During the 110 interval of silence caused by travel of the clapper from one side of the bell to the

other, one of the clappers 13 is caused to strike the edge of the bell through the force of gravity and sound the same, said clapper being returned to its normal position by the 5 spring after sounding the bell. Upon the return movement of the bell, that is, toward the opposite side of the turret or tower, the opposite clapper 13 is caused to strike the edge of the bell and sound the same. It is 10 of course obvious that none of the clappers strike the bell simultaneously, each clapper alternating so that the bell is practically sounded continuously with the exception of a small interval to permit the bell to adjust 15 itself and prevent striking of two of the clappers at once.

From the foregoing it will be readily seen that this invention provides a novel attachment capable of being applied to any conventional form of bell without requiring alterations. At the same time it lessens the intervals between strokes of the bell, and does not interfere with the vibration of the bell between strokes. Furthermore, it does 25 not require any special means of operation but is operated through the medium of the usual momentum of the bell.

What is claimed is:—

1. A device of the character described 30 comprising a bell having a clapper, a support carried by the bell, auxiliary clappers movably mounted on the support, and means carried by the support for normally urging the auxiliary clappers away from the outer 35 surface of the bell, said auxiliary clappers being operable independently of the main clapper.

2. The combination with a bell having a 40 clapper mounted interiorly thereof, of a support carried by and disposed exteriorly of the bell, auxiliary clappers movably mounted on the support, each of said clappers being adapted to alternately strike the bell upon oscillating movement of the bell.

45 3. A device of the character described

comprising a bell, a support carried by and projecting beyond the outer sides of the bell, clappers pivoted to the support, and means for holding said clappers in spaced relation to the exterior surface of the bell.

4. A device of the character described 50 comprising a bell, a support carried by and projecting beyond the outer sides of the bell, clappers pivoted to the support, and springs carried by the support and normally engaged with one end portion of the clappers to permit vibration of the bell, the projecting portions of the support coacting with the springs to normally hold the clappers in spaced relation to the bell.

5. An attachment for bells comprising a support adapted to be secured to the upper portion of the bell, the end portions of the support extending over the outer sides of the bell, a clapper pivoted at one end to each end portion of the support, a spring secured at one end to each end portion of the support, one end of each spring being adapted to engage one end of each of the clappers to normally hold said end of the clapper in 65 spaced relation to the bell.

6. An attachment for bells comprising a support adapted to be secured to the upper portion of the bell, the end portions of the support extending over the outer sides of the bell, a clapper pivoted at one end to each end portion of the support, a spring secured at one end to each end portion of the support, one end of each spring being adapted to engage one end of each of the clappers to normally hold said end of the clapper in 75 spaced relation to the bell, said clapper being adapted to overcome the resistance of the spring through the medium of gravity upon movement of the bell in the direction of the clapper.

In testimony whereof I hereunto affix my signature.

EDWARD J. TEKULVE.
